UNITED STATES PATENT OFFICE.

JOHN C. HANRAHAN, OF LOS ANGELES, CALIFORNIA.

STEAM BOILER.

Application filed February 3, 1922. Serial No. 533,874.

To all whom it may concern:

Be it known that I, JOHN C. HANRAHAN, a citizen of the United States, residing at Los Angeles, in the county of Los Angeles and 5 State of California, have invented new and useful Improvements in Steam Boilers, of which the following is a specification.

My invention relates to the generation of steam by improved method of generator construction, and a purpose of my invention is 10 the provision of a boiler furnace in which the drums constituting the boiler are so associated with each other, and the water supplied and the steam discharged from the 15 drums in such manner as to effect a duplex circulation of water within the boiler, thereby permitting of a wide fluctuation in the water level without injury to the drums and tubes constituting the boiler, and preventing 20 the escape of water from the steam discharge or "pulling over" caused by formation of steam pockets in the boiler tubes.

It is also a purpose of my invention to 25 provide a boiler furnace in which the boiler drums are effectively supported and in a manner to allow of the necessary diaphragm expansion and contraction of the parts comprising the boiler and without the possibility 30 of such parts being cracked or otherwise impaired.

A further purpose of my invention is the 35 provision of a boiler furnace including perforated baffles associated with the boiler tubes so as to in no way restrict the draft area and yet completely dissipate the unburnt combustible products and thereby promote perfect combustion.

I will describe one form of boiler furnace 40 embodying my invention and will then point out the novel features thereof in claims.

In the accompanying drawings,

Fig. 1 is a view showing in section and perspective one form of boiler furnace embodying my invention.

Fig. 2 is an enlarged fragmentary sectional view of two of the drums comprised in the boiler shown in Fig. 1 and the baffle and tube connection therein.

Fig. 3 is a view similar to Fig. 2 and taken 50 at right angles to the latter.

Fig. 4 is an enlarged fragmentary sectional view of one of the water legs comprised in the boiler furnace shown in Fig. 1.

Fig. 5 is a view showing in side elevation 55 the bottom or purifying drum of the boiler furnace shown in Fig. 1.

Similar reference characters refer to similar parts in each of the several views.

Referring specifically to the drawings and particularly to Fig. 1, my invention, in its present embodiment comprises a suitable base 14 upon which is supported a furnace structure including side walls 15 and 16 and an intermediate wall 17. Between the side walls and the intermediate wall and contacting with the former are subsidiary walls 18 and 19. The walls 15 and 16 are provided on their inner sides with shoulders 20 curved to accommodate boiler drums D and D' horizontally arranged and provided with water legs L and L' depending from the latter and positioned within suitable openings formed in the subsidiary walls 18 and 19. In the present instance I have shown the water legs L and L' sustained on tubular supporting 65 columns 21 arranged within the walls 18 and 19 and having their upper ends concave to accommodate the convex ends 22 of the water legs, all as clearly shown in Fig. 4. The lower ends of the water legs are provided with collars 23 adapted to receive the upper ends of the columns 21 and to thereby 70 provide a substantial connection between the legs and columns. 75

The upper edge of the intermediate wall 80 17 is convex to accommodate a drum D² which constitutes the purifier of the boiler, and superimposed upon the drum D² is a second intermediate wall 24 which is convexed at its upper and lower edges to conform in the latter instance to the contour of the drum D², and in the former instance to a drum D³ disposed between but above the drums D and D'. A fifth drum D⁴ is arranged above the drum D³ and a third intermediate wall 25 is interposed between the 85 latter and the drum D³.

As clearly shown in Fig. 1, the boiler furnace includes two fire boxes 26 and 27 of practical length at opposite sides of the intermediate wall 17, these fire boxes being provided with grates, as shown, which are preferably co-extensive in length with the drums D', etc. By virtue of this arrangement, the intermediate walls 17, 24, and 25 90 serve to collect and transfer heat to the several drums arranged on such walls, and more particularly the purifying drum D², thereby greatly assisting combustion and giving a wide grate area. The furnace structure includes a cover 28 convexed at 95 its medial portion and longitudinally to 100 105 110

provide a stack breeching 29 which communicates at its rear end with a chimney 30, it being particularly noted that the breeching is disposed in spaced relation to the uppermost drum D⁴.

The several drums D—D', etc. constituting the boiler are in communication with each other through relatively short tubes T which, as clearly shown in Figs. 1, 2 and 3, are extended through baffle blocks B, the latter constituting baffle walls for the purpose of retarding the passage of heat to promote perfect combustion. As shown in Figs. 2 and 3, the baffle blocks are provided with ducts 31 which extend transversely through the walls, and through these ducts the products of combustion are adapted to pass (as passing through a lid bored literally full of holes) in seeking their way from the fire box to the stack breeching, all as clearly indicated in Fig. 1. Referring to Fig. 1, D² is the first drum, and D' and D are respectively the second and third drums, D³ is the fourth drum and D⁴ is the fifth drum. The first set of tubes and baffle block A connects the first and second drums D² and D. The second set of tubes and baffle block B connects the drums D² and D'. The third and fourth sets C and E connect the second and third drums to the fourth drum and the fifth and sixth sets of tubes and baffle blocks F and G connect the second and third drums to the fifth drum. The baffles F and G terminate at their upper edges short of the drum D⁴ to allow the products of combustion to pass their upper edge into the chamber I which surrounds the upper part of the fifth drum and the products of combustion pass along said chamber under the breeching 29 to the smoke stack 30.

Water is adapted to be supplied to the purifying drum D² through a pipe P which, as clearly shown in Fig. 5, is connected to the forward end of the drum at a point adjacent its bottom so as to utilize the water force from a pump in effecting a rearward movement of any sediment contained in the drum to a blowoff or discharge pipe P', it being understood that the raw water meets a temperature so high that the impurities will be deposited in the purifying drum. The steam generated within the boiler is adapted to be conveyed to any remote point for use by a discharge pipe P³ which, as clearly shown in Fig. 1, communicates with the uppermost drum D⁴ and is extended through the stack breeching 29.

In the operation of the boiler furnace, combustible gases from the burning fuel in the fire boxes rise to the stack breeching in two main columns, and these main columns are divided into a multiplicity of small columns by forcing them to seek outlets through the perforated baffle blocks B. It will thus be seen that the distribution of

the active heat is effected over a wider area than is possible with the ordinary method of directing a flame through a single spot. Although the blocks B do retard the flow of gases, they do not consume the heat but serve to promote perfect combustion.

This operation prevents the distribution of the water impurities through the several drums as would occur if the water was initially introduced into the top drum D⁴. With the drums filled with water as shown in Fig. 1, a circulation of the water from drum to drum through the tubes T will occur when such water is heated to the boiling point thereby effecting a constant movement of the water in all of the drums and thus preventing the formation of cool spots.

A boiler so constructed that a furnace fits its contour, is a mandatory part of the structure, which finally results in an efficient combination of parts into a vastly improved steam generator. The construction is compact, strong and simple, and without complicated or inaccessible parts, hangers, beams or superstructural supports.

Although I have herein shown and described only one form of steam generator embodying my invention, it is to be understood that various changes and modifications may be made herein without departing from the spirit of the invention and the spirit and scope of the appended claims.

What I claim is:

1. A boiler comprising a base, an intermediate wall extending upwardly from the base, a drum upon the intermediate wall, fire boxes at the sides of the intermediate wall in a plane below the drum, side walls outside of the fire boxes, second and third drums imbedded into the side walls and having water legs extending downwardly to the level of the fire boxes and columns extending from the water legs to the base, inclined tubes connecting the first drum to the second and third drums, a second intermediate wall extending upwardly from the first drum, a fourth drum resting upon the second intermediate wall, tubes connecting the fourth drum to the second and third drums, a fifth drum above the fourth drum, tubes connecting the fifth drum to the fourth drum, said side walls extending upwardly near to the plane of the bottom of the fifth drum, said walls being spaced from the fifth drum at the upper edge, and a stack breeching resting upon the side walls and extending over the fifth drum and spaced therefrom.

2. In a steam boiler construction, an intermediate wall, a boiler drum above the intermediate wall, fire boxes at each side of the intermediate wall and having grates in a plane below the drum, side walls outside of the fire boxes, a second boiler drum at the opposite side of one fire box from the

first drum and in a higher plane, tubes connecting the second drum to the first drum, baffle blocks upon the tubes against the drums and having perforations for the passage of heat, a third drum at the outer side of the other fire box and in the same plane as the second drum, tubes connecting the third drum to the first drum, baffle blocks upon the tubes and against the drums and having perforations for the passage of heat, water legs extending downwardly from the second and third drums outside of the fire boxes, a second intermediate wall extending upwardly from the first drum, a fourth wall, tubes connecting the fourth drum to the second and third drums, a fifth drum above the fourth drum, tubes connecting the fifth drum to the second and third drums, baffle blocks upon the third and fourth sets of tubes and having perforations for the passage of heat, and walls outside of the fifth and sixth sets of tubes, said walls terminating short of the fifth drum for the passage of heat over the upper edges and a breeching over the fifth drum into which the products of combustion discharge.
